ATTORNEY.

UNITED STATES PATENT OFFICE.

JAY R. MCCOLL, OF DETROIT, MICHIGAN.

VENTILATING SYSTEM.

Application filed May 27, 1922. Serial No. 584,067.

To all whom it may concern:

Be it known that I, JAY R. MCCOLL, a citizen of the United States, and residing at Detroit, in the county of Wayne and State 5 of Michigan, have invented a new and Improved Ventilating System, of which the following is a specification.

This invention relates to means for supplying fresh air to school rooms, churches 10 and similar places of assembly where many persons congregate, and its object is to provide a ventilating system by means of which the air can be discharged from a series of suitable openings in the ceilings of such rooms 15 and so directed by proper diffusers that every portion of such rooms will receive an adequate amount. A further object of this invention is a system of this character which shall be built into the ceiling and walls of 20 the room in which it is installed.

This invention consists in a ventilating system for assembly rooms in which a concrete slab is provided with an air conduit having a number of discharge openings in 25 its lower side, and a diffuser mounted in the conduit adjacent each opening and provided with vanes for causing the air issuing from the opening to spread out to substantially pyramidal form.

It also consists in adjustable deflectors attached to the several diffusers to control the volume of air passing through each diffuser.

It further consists of the details of construction illustrated in the accompanying 35 drawings and particularly pointed out in the claims.

In the accompanying drawings, Fig. 1 is a vertical section of the walls, ceiling and floor of a room of a building provided with my 40 improved system of ventilation. Fig. 2 is a bottom plan of a ceiling. Fig. 3 is a central longitudinal section of a portion of a ceiling air-conduit. Fig. 4 is a section on the line 4-4 of Fig. 3. Fig. 5 is a detail of the 45 construction of a ceiling conduit. Fig. 6 is a cross section of a modified form of conduit between diffusers. Fig. 7 is a bottom plan of the frame at a diffuser opening.

Similar reference characters refer to like 50 parts throughout the several views.

Ventilation and heating engineers are practically agreed that air of proper temperature should be forced into assembly rooms through openings which will give 55 good distribution and this air should be permitted to escape through openings at the

bottoms of the walls of such rooms. The openings in the ceilings are ideal and should be so spaced that the pyramids of air coming therefrom shall unite no lower than the 60 level of the heads of the persons occupying such rooms. The floors and ceilings of many buildings are now constructed of reinforced concrete which is molded over and between parallel rows of terra-cotta tiles 65 or sheet metal forms, the latter being used in increasing proportions.

As a rule, these sheet metal forms are 70 usually corrugated at both tops and sides so that they are unacceptable as air conduits owing to the excessive resistance of the corrugated surfaces to the flow of air. I therefore provide the conduits shown in the drawings, consisting of tops 1 and sides 2 which are preferably at the same angles to 75 the top as the sides of the floor forms 3. The concrete 4 is molded over the tops and along the sides of these air conduits to constitute the floors of the buildings, reinforcing bars of steel of any desired construction being employed. As the tops 1 of these conduits are flat, posts or braces 6 of flat bar steel are positioned as closely as necessary between the normal bottom plate 7 of the conduit and the reinforcing angle 8 extending along the top thereof. The open 80 mesh metal lath 9 and plastering 10 extend across below the bottoms of the side walls of these air conduits and of the floor forms 3.

The number of these air conduits in a ceiling and therefore the distance between them will depend upon the size of the room to be ventilated and the height of the ceiling, more conduits being required in a low room than in one with high ceilings, the latter permitting higher air pressures. At intervals along the conduits the ceiling and the bottom plates 7 of the conduits are formed with openings, bordered with the flat bars 12 and 13. If desired, a grate or screen 14 may be held in position by these flat bars. Or these bars 12 and 13 may be formed parts of the register.

The lower edges of the sides 2 of these air 105 conduits, along and at each side of these openings, are turned in to constitute the flanges 15, then down to constitute the borders 16 and then out to constitute the flanges 17, extending around three sides of the wood strips 18 which are adapted to receive the screws 19 by which the bars 12 and 13 are 110 secured. I prefer to reinforce these portions

of the conduit walls by angle bars 20, attached to these bent portions of the walls and the strips 18 by bolts 22. These angle bars are preferably longer than the openings, as indicated in Fig. 7.

The bottom plates 7 of the air conduits are preferably offset downward just as these air openings, as shown at 23, and fit the cross strips 24 of wood, as shown in Fig. 3.

A diffuser, such as shown in Figs. 3 and 4, is mounted within the air conduit at each ceiling opening. It comprises a plate 26 turned down at 27 and then outward to constitute the flange 28 (Fig. 3). One edge is formed into hooks 29 to extend through slots 30 in one edge of a deflector 31 at the inlet of each diffuser. The side plates 32 of each diffuser extend from the plate 26—27 and I prefer to stiffen the lower edges of these side plates by means of the angle bars 34, which normally rest on the bars 12. An angle bar 35 extends between the lower corners of the side plates 32 adjacent the strip 24 and rests on a bar 13. Gaskets 37 of felt or other desirable material may be placed between the edges 17 of the side walls 2 of the conduits and the angle bars 34 and between the edges 23 of the bottom plates of the conduit and the flange 28 on the plate 26—27 of the diffuser and the angle bar 35 respectively.

Attached to the angle bar 35 is a brace 38 which carries an adjusting screw which extends through a nut 41, pivoted to the bracket 40 (Fig. 4) on the deflector 31. As indicated in Fig. 1, these deflectors are placed at such angles that substantially the desired amounts of air will pass down through the several diffusers.

I prefer to form the diffusers with dividing plates 42 which cause the air to issue at wider angles longitudinally of the conduits and with the flaring vanes 43 which cause the air to issue at wider angles transversely to the conduits. These dividing plates and vanes cause a very uniform flow of air in all parts of the pyramids of air descending from these diffusers, that is, instead of a pyramid of air of which the middle portion moves down much more swiftly than the outer portions, a pyramid is pro-

duced wherein the flow of the several portions is more nearly equal. The person sitting directly beneath a diffuser will therefore receive but little more fresh air than the person sitting beneath a point midway between two diffusers.

The air conduits in the floors may connect to main air conduits or tunnels 45 in any desired manner, the vertical flues or ducts 46 being indicated, these being formed in a side or partition wall 47. It will be understood, however, that any other desired type of air supply may be employed. This air may be heated or cooled if desired.

The details of construction and the proportions of parts may all be changed by those skilled in the art without departing from the spirit of my invention as set forth in the following claims.

I claim:

1. In a ventilating system for rooms, a ceiling construction embodying an air conduit having openings in its lower side, a diffuser mounted in the lower part of the conduit at each opening and comprising sides, a top and an upright end, a partition plate extending between the sides substantially parallel to the top and end, vanes extending longitudinally of and substantially within the conduit in each direction from that portion of the partition plate which is parallel to the end of the diffuser, and an adjustable gate mounted within the conduit adjacent each of the diffusers to determine the proportion of the air passing through the conduit which shall pass through the adjacent diffuser.

2. In a ventilating system for rooms, a ceiling construction embodying an air conduit having openings in its lower side, a diffuser mounted in the lower part of the conduit at each opening and comprising sides, a top and an upright end, vanes extending longitudinally of and substantially within the conduit, and an adjustable gate mounted within the conduit adjacent each of the diffusers to determine the proportion of the air passing through the conduit which shall pass through the adjacent diffuser.

JAY R. McCOLL.
